UNITED STATES PATENT OFFICE.

IGNATIUS SMITH, OF NEW YORK, N. Y., ASSIGNOR TO BUREAU OF THE HOLY NAME SOCIETY, OF NEW YORK, N. Y.

DESIGN FOR A BUTTON, BADGE, OR ARTICLE OF SIMILAR NATURE.

58,949.

Specification for Design.

Patented Sept. 6, 1921.

Application filed June 19, 1920. Serial No. 390,257. Term of patent 14 years.

To all whom it may concern:

Be it known that I, IGNATIUS SMITH, a citizen of the United States, residing at New York, in the county of New York and State of New York, have invented a new, original, and ornamental Design for Buttons, Badges, or Articles of Similar Nature, of which the following is a specification, reference being had to the accompanying drawing, forming part thereof.

The figure shows a front elevational view of the new design, of button or badge.

I claim:

The ornamental design for a button, badge, or article of similar nature as shown.

IGNATIUS SMITH.
